UNITED STATES PATENT OFFICE.

GEORGE JOHNSTON, OF MANCHESTER, ENGLAND.

APPARATUS FOR PULVERIZING ORE AND THE LIKE.

1,396,711.

Specification of Letters Patent.

Patented Nov. 8, 1921.

Application filed August 15, 1921. Serial No. 492,458.

To all whom it may concern:

Be it known that I, GEORGE JOHNSTON, a subject of the King of Great Britain and Ireland, and a resident of Manchester, England, have invented certain new and useful Apparatus for Pulverizing Ore and the like, for which I have filed British patent application No. 32,672, dated July 30, 1920, of which the following is a specification.

10 The invention has for its object to provide a type of apparatus for pulverizing ore or the like by direct crushing with the substantial elimination of abrasive action either upon the ore crushed or upon the surfaces 15 by which it is crushed.

A unit apparatus made according to the invention, comprises a pair of rolls of comparatively narrow face and of as great hardness of face as may be. These rolls are 20 carried in headstocks provided with usual overload release gear, and means are provided for the accurate adjustment of the pass between them. The rolls are driven at a comparatively high peripheral speed, and 25 the particles of material to be crushed are fed to them at a velocity as nearly as may be equal to that peripheral speed and in such wise that the particles are presented to the rolls successively and as nearly as may 30 be separately—that is to say that each particle is presented with space between it and adjacent particles. Various means for carrying out these, the two essential features of the invention, may be provided, but very 35 conveniently the material is delivered to the rolls through a narrow slot-like hopper which may have a central partition. The material is caused to flow through the hopper to the rolls (with a velocity substantially that of the rolls' surface) and away from the rolls after being crushed, by an induced current of air.

A series of these unit pairs of rolls operating upon the material and with the pass of 45 each successive pair adjusted to break down the material successively, a determinate amount is preferably provided, each successive pair of rolls being driven at that greater speed determined by the successive 50 and gradual comminution of the material and so that in all cases the material enters between the rolls with as nearly as may be the velocity of their surfaces. The material is crushed to travel from roll to roll by an 55 induced stream of air and is finally delivered to a settling chamber or directly to

a lixiviation vat by that current. It is delivered from one pair of rolls on to a guiding device, preferably consisting of a series of triangular and slightly oppositely inclined 60 teeth, from which it passes to ducts, from whence it is delivered to the next pair of rolls.

The rolls are preferably carried in bearing blocks guided in the headstocks, and are urged together by heavy springs forming the relief devices. They are preferably adjusted for width of pass by cams carried on spindles parallel with and between the axes of the rolls and pressing equally and oppositely upon the bearing blocks. The cams are operated through trains of gearing provided with pointers indicating on suitably enhanced scales, the width of the pass. Detachable means for truing the rolls by grinding may be provided.

An apparatus comprising a series of rolls is totally inclosed in an air-tight casing so that not only may the induced stream of air necessary to cause the flow of material 80 to the rolls and from pair to pair be readily maintained, but also so that the discharge of dust from the apparatus may be avoided.

In the accompanying drawing—

Figure 1 is a broken end elevation of a 85 crusher unit employing two pairs of rolls.

Fig. 2 is a broken perspective illustrating the toothed divider bar for breaking up the more or less sheeted material delivered by the crusher rolls.

Fig. 3 is a vertical section showing the driving gear for the rolls and the fan for creating the suction feed draft through the crushers.

In this example the upper pair A, B of 95 rolls and the lower pair C, D are carried in usual bearing blocks E sliding in headstocks F, and the rolls of each pair are urged toward one another by heavy springs G forming also the usual relief devices.

The necessary accuracy of adjustment for width of pass of each pair of rolls is provided by cams H carried at each side of the housing by spindles J. On the spindles J are spur-wheels K gearing with pinions L 105 on a shaft M extending from housing to housing. On the shaft M, externally to the housings, are disks N by rotation of which adjustment of the cams H is brought about. The disks bear indications of the adjustment 110 and are locked by fingers I serving as pointers to the indications and pressed down upon

the disks by nuts. Rolls and their headstocks are as nearly as may be, totally enclosed in casings Q as airtight as possible.

The material to be treated is drawn in at 5 an inlet aperture R by a suction fan O (Fig. 3) connected to outlet apertures S. The inlet aperture has within it a diaphragm T dividing the ingoing stream of air and material into two portions directed upon the 10 peripheries of the rolls A, B close to the point of pass, and which rolls are driven by belts P on pulleys U at a surface speed as nearly as may be that of the stream.

From the nip of the rolls A, B the material 15 passes to a guiding device V which bears upon its top a series of comparatively narrow triangular teeth W, alternate ones of which are slightly oppositely inclined. From the guiding device V, the material 20 passes by way of ducts X formed in the casing, to the second pair of rolls C, D the nip of which is narrower and the surface speed of which (driven by pulleys Y) is 25 proportionately greater. From the second pair of rolls the comminuted material passes over a device Z similar to the device V and from thence to the outlets S, from which it is delivered to a settling chamber, or it may be, 30 directly to lixiviating vats, or to similar machines for further treatment.

What I claim is:—

1. In pulverizing apparatus, a pair of crushing rolls and means arranged adjacent the nip of the rolls for guiding air-propelled material thereto and means for propelling said material and rotating said rolls at substantially the same speed.

2. In pulverizing apparatus, a pair of crushing rolls and a feed device for delivering material to the nip of the rolls, said device comprising a feed duct having a guide plate extending into the area between the rolls adjacent the nip and channel means for leading material under the influence of an impelling blast past said guide plate to the nip of the rolls.

3. In pulverizing apparatus, a pair of crushing rolls and a feed device for delivering material to the nip of the rolls, said device comprising a feed duct having a guide plate extending into the area between the rolls and adjacent the nip, and channel means for leading material under the influence of an impelling blast on opposite sides 55 of said guide plate to the nip of the rolls.

4. In pulverizing apparatus, a pair of high speed crushing rolls, and an air-feed duct opening to the nip of the rolls and adjacent the latter for leading material to the 60 rolls and means for propelling said material and rotating said rolls at substantially the same speed.

5. In pulverizing apparatus, a pair of

high speed crushing rolls, and an air feed duct comprising a feed guide plate extending to a point adjacent the nip of the rolls for the purpose specified.

6. In pulverizing apparatus, a pair of high speed crushing rolls, and an abutment against which the partially-crushed and 70 caked material is discharged, said abutment tending to break up the adhesion between the particles of the cake under the influence of its impact.

7. In pulverizing apparatus, a pair of 75 crushing rolls, means for diverting the discharge therefor at an angle to its normal direction of delivery, and an air channel, arranged at an angle to the flow of said diverted material, to which the latter is delivered.

8. In pulverizing apparatus, successive pairs of crushing rolls, means for delivering the partially crushed material from the first pair of rolls to an air channel lying at an 85 angle to the direction of the flow of said discharged material, said channel leading to the succeeding pair of rolls to feed thereto the partially crushed material with its particles disassociated.

9. In pulverizing apparatus, successive pairs of crushing rolls, means for delivering material from the first pair of rolls to an air channel having a curvilinear course in which adhesion between the particles of the 95 caked material discharged from the first rolls is broken up, said channel leading to the succeeding pair of rolls for the delivery thereto of the partially crushed material with its adhering particles disassociated.

10. In pulverizing apparatus, successive pairs of crushing rolls, air channel means for delivering to the first pair of rolls the material to be crushed, an air channel bypassing said rolls and leading to the second 105 pair of rolls, and means for delivering the partially crushed material from the first pair of rolls to said channel to insure its delivery to the second pair of rolls.

11. In pulverizing apparatus, successive 110 pairs of crushing rolls, air channel means for delivering to the first pair of rolls the material to be crushed, an air channel bypassing said rolls and leading to the second pair of rolls, means for delivering the partially crushed material from the first pair of rolls to said channel to insure its delivery to the second pair of rolls, and means for breaking up the adhesion between the particles of caked or sheeted material delivered 115 from the first pair of rolls, before it is fed to the second pair.

In testimony whereof I have signed my name to this specification.

GEORGE JOHNSTON.
